COMBINED DRINKING CUP AND INSULATING HOLDER THEREFOR

Eugene J. Riley, 613 N. West St.,
Anaheim, Calif. 92801

Filed Mar. 22, 1968, Ser. No. 11,099

Term of patent 14 years

Int. Cl. D7—01

U.S. CL. D44—9

FIG. 1.

FIG. 2.

FIG. 4.

FIG. 3.

FIG. 6.

FIG. 5.

FIG. 1 is a perspective view of a combined drinking cup and insulating holder therefor showing my new design;

FIG. 2 is a right side elevation view;

FIG. 3 is a top plan view;

FIG. 4 is a bottom plan view;

FIG. 5 is a perspective view of the cup member; and

FIG. 6 is a perspective view of the holder member.

I claim:

The ornamental design for a combined drinking cup and insulating holder therefor, substantially as shown.
